ARRANGEMENT IN STRIKING TOOL

Application filed December 4, 1928. Serial No. 323,786.

This invention relates to improvements in striking tools of the power-operated type adapted for use in connection with boring, punching and like machines wherein the 5 striking body is mounted to move axially and cooperates with an independently movable anvil coacting with the tool.

The invention has for its object to provide means whereby the tool may be readily removed, adjusted or replaced without interrupting the operation of the implement whereby during such operation the tool is not subjected to the action of the striking body.

15 A further object of the invention is the provision of means of the character above stated which normally acts to maintain the anvil in a position removed from the path of the striking body, but which, upon application of the tool to use, permits axial movement of the anvil to a position within striking distance of the striking body.

20 A further object of the invention is the provision of a device of this character in which the anvil is prevented from rotating during removal or replacement of the tool.

In the accompanying drawing wherein an approved embodiment of the invention is illustrated

25 Fig. 1 is a longitudinal section view of an implement constructed in accordance with the invention.

Referring to the drawing in detail, the numeral 1 indicates a striking body which 30 is mounted for axial movement in a guide sleeve 2 which latter is maintained in constant operation during the use of the implement by an electric drive motor mounted in the implement frame 3. The axially movable and rotatable anvil 4 is mounted in the frame 3 and coacts with an adjacent end of a tool 5. The mutually facing terminals of the striking body 1 and anvil 4 are provided with cam faces 6 and 7 which at the moment 35 of contact between the two parts, effects recoil of the rapidly rotating striking body 1. Centrifugal bodies 8 preferably of spherical form are mounted to move axially in recess 40 provided in the striking body 1, and coacting with inclined guide faces 10 are moved

inwardly towards the axis of the striking body during recoil movement of the latter. When the recoil movement of the striking body 1 is completed, the centrifugal bodies 8 revolve rapidly with the guide sleeve 2 and body 1 and are subjected to the effects of centrifugal force, and coacting with the inclined guide faces 10 urge the striking body 1 in the direction of the anvil 4, thus completing the working stroke of the striking body and causing it to deliver a blow upon the anvil 4.

In the event that the striking movement of the body 1 is not arrested by engagement with the anvil 4, due to the disposal of the latter in a position removed from the path of the striking body, the outward striking movement of the latter is limited by the centrifugal bodies 8 coacting with the inwardly converging terminal walls 11 of the grooves or 50 guide faces 10. On the other hand, if the anvil 4 is disposed in a position within the range of movement of the striking body the latter delivers a working stroke thereto.

The anvil 4 is normally retained in forwardly or outwardly projected position, during periods of inoperativeness of the implement, by the tension of a spring 12 confined between a guide part 13 and a bearing ring 14 coacting with bearing balls 15 which 55 latter are partially received in a groove 16 formed in a contiguous part of the anvil 4. Thus, the ring 14 constitutes both a bearing or abutment for the spring 12 and part of the bearing for the adjacent terminal of the 60 anvil 14. The outward movement of the anvil is limited by a shoulder 17 coacting with an adjacent portion of the guide part 13.

The shoulder 17 is preferably inclined or 65 of frusto-conical form, and the adjacent portion of the guide part 13 is correspondingly shaped so that when the anvil is moved outwardly under the influence of the spring 12 the inclined shoulder 17 and cooperating portion 22 of the part 13 coacts to retard or 70 brake the rotational movement of the anvil, such movement having been imparted thereto by its engagement with the rapidly rotating striking body 1.

In accordance with the arrangement herein described, when the implement is not in use the anvil 4 is retained in outwardly projected position under the influence of the spring 12, and is so disposed that the cam face 6 is removed from the corresponding face of the striking body 1, and the latter is therefore prevented from acting upon the anvil during its rotary movement. During the period of inactivity of the anvil 4, it is thus possible to conveniently and quickly apply, remove, or interchange the tool 5, and in so doing the anvil is prevented from accidental turning movement due to the co-action of the inclined shoulder 17 with the wall 22 of the guide part 13. However, when the implement is to be used, the tool 5, as usual, is applied to the work, and the pressure on the anvil 4 resulting from such application displaces said anvil inwardly against the tension of the spring 12 until its cam face 7 is engaged by the cam face 6 of the striking body, whereupon the implement is set in operation.

What I claim is:

In an implement of the character described, a frame, a striking body mounted for axial and rotating movement in said frame, an anvil mounted for rotary and axial movement in said frame and engageable by said striking body, means normally retaining the anvil in outwardly projected inoperative position, and means acting to retard rotary movement of the anvil when the latter is in inoperative position, said last mentioned means including a member carried by the frame, and an inclined shoulder on the anvil coacting with said member.

In testimony whereof I affix my signature.

ERIK GUSTAF HYSING.
